*Fig 7**Fig 8*

FIGURE 1 is a perspective view of a portable viewer for microfilm adapted to receive tape cartridges and employing an open well together with a viewing screen having a 3 to 2 relationship to the lid width;

FIGURE 2 is a side elevational view of FIGURE 1;

FIGURE 3 is a front elevational view of FIGURE 1;
FIGURE 4 is a top plan view of FIGURE 1;

FIGURE 5 is a viewer design similar to that of FIGURE 1 adapted to receive aperture cards and employing a viewing screen of substantially the full width together with a covered well portion;

FIGURE 6 is a side elevational view of FIGURE 5;

FIGURE 7 is a front elevational view of FIGURE 5;
FIGURE 8 is a top plan view of FIGURE 5.

The broken line electrical cords in FIGURES 1 and 5 are shown only for illustrative purposes. The diagonal shade lines in FIGURES 1, 3, 5 and 7 represent a translucent back projection screen.

This application is a continuation of U.S. design applications Ser. No. 7,485, filed June 15, 1967, and Ser. No. 7,486, filed June 15, 1967, and now abandoned.

I claim:

The ornamental design for a portable viewer for microfilm or the like, substantially as shown and described.
